SUBMARINE GUN

Charles H. Wilen, Brooklyn, N. Y.

Application December 10, 1940, Serial No. 369,371

12 Claims.

(Cl. 43—6)

This invention relates to improvements in what may be termed a submarine gun for shooting fish by means of an arrowlike or elongated pointed member which is discharged from the gun by a person while swimming or being submerged under water.

It is a well-known fact that a person swimming under water or submerged in the water can approach within a few feet of any fish that may be present, and because of this fact the fish can be shot and captured by the gun to be hereinafter described. This gun has many essential improvements over the original form of gun which I have used for shooting fish under water. These improvements or advantages may be summarized as follows:

In the original type of gun, using a long tube and an elongated pointed member for compressing a spring within the tube, the force of the discharge, due to the powerful spring, was so great and the departure of the arrow so rapid that a vacuum was created in the barrel of the gun which retarded and weakened the force of the arrow. To overcome this difficulty, I have provided a plurality of holes arranged longitudinally of the tube or barrel of the gun, which holes are small enough so as not to weaken the tube, yet large enough to admit water when the gun is discharged. This breaks up the vacuum and overcomes this difficulty.

Another advantage is that, in the form of gun to be herein described, the pistol grip handle is so placed that when the gun is loaded and being carried while swimming, it is in perfect balance and may be aimed while being held in one hand, allowing the arm of that hand to be stretched outwardly to its maximum distance; this gives added approach to the fish or target. Furthermore, the pistol grip is so constructed that the trigger may be fired by two fingers of one hand, while the grip is held by the other two fingers.

A further advantage is that the gun is provided with a loading catch so constructed and arranged that once the arrowlike member is gripped by it, the arrow can only be discharged by pulling the trigger into releasing position. After the arrowlike member has been locked to discharge position, pulling on the arrow only serves to lock it tightly against the catch, which feature is of great value as it prevents accidental discharge of the gun due to a weak loading grip as exists in guns of this type which I have heretofore used.

A further advantage is that the safety of the gun is further assured by the use of a thumb

5 safety catch which, after the gun is loaded, can be moved to effectively lock the trigger so that the loaded gun may be left, with the danger being reduced to a minimum of children or others accidentally pulling the trigger and discharging the gun.

10 A further advantage is that the gun barrel or tube is made in two parts, one of which remains with the hand grip, while the other may be removed and the two portions folded up, since the spring will allow this, thereby allowing the gun to be reduced in length for greater ease in carrying or transporting.

15 These and other advantages will be discerned from a reading of the following specification, taken in connection with the annexed drawings, wherein:

20 Figure 1 is a side view of the greater portion of the gun, the forward part being shown in elevation and the rear part partly in section and partly in elevation, and with the gun in loaded position, the trigger being locked.

25 Figure 2 is a top view of Figure 1, with the parts of the hand grip shown in section.

Figure 3 is a section on the line 3—3 of Figure 2 but showing the anchor bolt in elevation.

30 Figure 4 is a view of the left-hand or firing end of Figure 1, partly in elevation and partly in section, showing the loading pin in dotted position.

Figure 5 is a view somewhat like Figure 1, but with the trigger and catch locked in a non-loading position.

35 Figure 6 is a view similar to Figure 5, but with the trigger and associated parts just operated and the discharge of the arrowlike member just beginning.

Figure 7 is a completely assembled view of the grip member looking at the reverse side of Figure 5.

40 Figure 8 is a side elevation of the loading catch.

Figure 9 is a view of the right-hand end of Figure 8.

45 Figure 10 is a view of the left-hand end of the trigger arm which engages the end of the loading catch shown in Figure 8.

Figure 11 is a partial bottom view of one of the gun barrel parts just adjacent the hand grip.

50 Figure 12 is a partial view of the elongated arrowlike member showing the end which engages the discharge spring.

Figure 13 is a view on a small scale showing the gun and the arrowlike member with the interconnecting cord.

Figure 14 shows the two parts of the gun disconnected and folded up for ease in carrying.

Figure 15 shows a modified form of the extremity of the projectile or harpoon end of the arrowlike member.

Referring now to the details wherein like numbers refer to corresponding parts in the various views, 1 and 2 are two tubes which meet at 3 within the two parts 4 and 5 of a hand grip which are arcuately formed at the top portion to receive the ends of the tubes 1 and 2, thereby forming a two-part combination tube which is held in alignment by the two parts of the hand grip when these parts are fastened together as by screw studs 6, 7 and 8 which have smooth portions for pivotally supporting parts to be hereinafter referred to.

The tube 2 is provided with dowel pins 9 and 10 which enter holes in the grip members 4 and 5 respectively, thereby preventing the tube 2 from turning in the hand grip. Fastened to the tube 1, as by a plurality of screws 11, is a guide block 12 which is adapted to fit into a slotted portion of the end 13 of the two parts of the hand grip, thereby preventing the tube 1 from turning in the hand grip members. A set screw 14 carried by the block 12 serves to lock the block and the tube 1 to the two hand grips, it being understood that the large stem portion of the screw 14 overlaps the two end portions 13 of the hand grip members 4 and 5.

Each of the tube members 1 and 2 is provided with a plurality of longitudinally spaced holes 15 for the purpose of preventing the arrowlike member 16, when it is forced outwardly by the spring 17, from creating a vacuum in the two-part combination tube. One end of the discharge spring 17 is formed into a ring and set into a block 18 and is anchored into position by a bolt 19 passing through the ring and the block 18, as well as a reenforcing cap 20. The cap 20 has a groove or channel therein to receive a light spring 21 which is also held in place by the bolt 19. The spring 21 has a conically shaped detent 22 to engage the surface of the tube 2, or preferably a slightly conical projection thereon, the purpose of which will be later described.

The tube 1 carries a reel 23 from which a cord 24 extends. A support guide 25 for the cord 24 is provided immediately adjacent the reel 23, and a further support and guide 26 is provided at the extremity of the tube 1.

Housed within the two grip members 4 and 5, and pivoted on the holding screw stud 7, is a trigger having a slotted arm 27 which carries a pin 28. The pin 28 is adapted to operate in a slot 29 in the loading catch 30 which has a pivot hole 31 to receive the smooth part of the screw stud 6. The catch 30 has a slight groove 32 to allow the spring 17 to pass freely over its end and to better fit around the reduced portion or seat 34 adjacent an abutment 35 formed at the end of the projectile or arrowlike member 16. The trigger has a finger-engaging portion 36 having an arm 37 extending rearwardly therefrom and having a projection 38 extending at an angle to the arm. To this end of the arm a spring 39 is attached, while the other end is attached to a screw stud 40 which also acts to fasten the lower end of the grip members 4 and 5 together. The spring 39 acts to normally pull downwardly on the arm 37 and this moves the trigger to push the catch 30 into arrow-engaging position as shown in Figure 1.

Housed within the hand grip parts 4 and 5 is

a safety catch 41 which is pivoted on the smooth part of the screw stud 8. Fastened to the safety catch 41 is an operating stud 42 which has a shank portion to slidably move in a slot 43 in the hand grip portion 5. The outer end of the stud 42 carries a thumb nut 44 for moving the catch 41 which is provided with a finger 45 adapted to be moved into the path of the projection 38 as indicated in Figure 1, to prevent the trigger from being operated to discharge the arrow.

By pushing upwardly on the thumb nut 44 (see Figure 14), the safety catch 41 is moved to the position shown in Figure 6, whereby the trigger may be operated and the gun discharged. By holding the trigger in the position shown in Figure 6 and pushing the thumb nut 44 downwardly, the safety catch 41 is moved to the position shown in Figure 5 wherein the projection 38 and the finger 45 interlock to prevent the arrow from being locked into discharging position.

As shown in Figure 11, the tube 1 is cut away at 46 and slotted at 47 to provide a space for the loading catch 30.

As shown in Figure 13, the end of the cord 24 is attached to the projectile or arrowlike member by reason of a hole 48 therein. At the end of the projectile or arrowlike member, a harpoon end 49 may be attached as by a screw-threaded end 50. The harpoon end of the projectile may be provided with a catch 51 pivoted at 52 and normally held by friction in the position shown in Figure 4, but after the fish has been shot, the catch 51 may move at an angle to the portion 49 to lock the arrow to the prey.

I have found that with the usual type of projectile end, if the arrow misses the fish and hits a rock, the force is great enough so as to either distort the shaft of the arrow or smash its point, or both, so I propose to insert in the end of the arrow a sharp point 53 which may be somewhat like a phonograph needle, which is inserted in a socket 54 that rests against a resilient cushion 55 preferably of soft rubber, so that in case of a miss, the impact will only destroy the needle point 53 which can be readily replaced. This construction obviates the trouble previously referred to.

In order to provide a relatively free length of line to allow the arrow more freedom in its travel after it leaves the gun or tube 1, with the least braking action possible, I prefer to loop the cord 24 back toward the rear of the gun and pass it under the light spring 21 which sits in a recess as previously described, so it cannot turn around the bolt 19. A slight pull on the cord will cause it to pass free of the projection 22 and allow the projectile to gain considerable momentum before it has to overcome the resistance of the reel 23.

In order to more easily load the gun, I provide a hole 56 in the end of the arrowlike member adjacent the harpoon portion 49, through which hole a pin 57, shown in dotted lines in Figure 4, may be inserted, thereby providing a hand grip to force the projectile into the gun barrel into locking position. In some cases, the harpoon portion 49 may be provided with a hole 58 for the same purpose.

In Figure 14 I have shown the two parts 1 and 2 of the gun disconnected and folded back with the spring 17 so that the gun may be placed in a short carrying casing.

The gun tubes 1 and 2 are preferably made of Duralumin which is strong enough to stand the

strain of loading, yet light enough to be easily carried by an ordinary swimmer. I have found that this is also sufficiently resistant to salt water so that with ordinary care, such as rinsing with fresh water after several hours' use in salt water, no corrosion occurs. The loading spring 17 and the trigger spring 39 may be made of stainless steel or beryllium to avoid oxidation in salt water and to reduce care-taking and cleaning to a minimum. All other steel parts are preferably made of stainless steel or plated with a material to reduce rusting to a minimum.

While I have shown a loading pin 51, the gun can be reset or loaded without the pin but not so easily. As a matter of fact, the gun can be reset or loaded without the user or swimmer coming out of the water. This can be done by resting the hand grip on the top of one foot while "treading water" and pushing in the projectile 16.

From what has been said, it will be seen that the various advantages set forth in the early part of the specification are attained through the medium of a rather simple and inexpensive construction, all of which has added greatly to the commercial possibilities of such a device.

What I claim is:

1. A submarine gun including an elongated, two-part combination tube with means for locking the two parts in alignment, a hand-grip positioned near the union of the two parts, a catch carried by the hand grip and adapted to engage a notch in an arrowlike member adapted to be inserted into the ejector end of the combination tube, a trigger also carried by the hand grip and operatively connected to said catch, a compressible spring positioned in both parts of the tube when the arrowlike member is absent from the tube, one end of the spring being anchored to the end of the combination tube opposite the ejector end, and a line attached at one end to an intermediate portion of the tube and having its other end adapted to be connected to the arrowlike member.

2. A submarine gun including an elongated, two-part combination tube, a hand grip having means for holding the two parts of the tube in alignment, each part of the combination tube having spaced openings along its length, a catch carried by the hand grip and adapted to engage a notch in an arrowlike member adapted to be inserted into the ejector end of the combination tube, a trigger also carried by the hand grip and operatively connected to said catch, a compressible spring positioned in both parts of the tube when the arrowlike member is absent from the tube, one end of the spring being anchored to the end of the combination tube opposite the ejector end, and a line attached at one end to an intermediate portion of the tube and having its other end adapted to be connected to the arrowlike member.

3. A submarine gun including an elongated, two-part combination tube, a hand grip having means for holding the two parts of the tube in alignment, a compressible spring normally positioned in both parts of the tube and anchored to the end of one, said holding means including a device carried by the hand grip and operable from the exterior of said grip, whereby the two parts of the combination tube may be readily separated and folded up along with the spring for convenience in transporting, a catch carried by the hand grip and having a part adapted to engage a notch in an arrowlike member adapted to be inserted into the ejector end of the com-

bination tube, a trigger also carried by the hand grip and operatively connected to said catch, and a line attached at one end to an intermediate portion of the tube and having its other end adapted to be connected to the arrowlike member.

4. A submarine fishing gun for discharging an arrowlike member having one end of a line connected thereto and including an elongated tandemly arranged plural-part tube having a part to which the line is connected, each tube part having a plurality of spaced relief openings along their length, a firing spring positioned, when not compressed, in the parts of the tube, the spring having one end anchored to one end of the tube and adapted to be compressed by the arrowlike member adapted to be inserted into the ejector end of the tube, a hand grip interconnected with the tube, a catch carried by the hand grip for holding the arrowlike member when it is inserted into the tube to compress the spring to ejection position, a trigger also carried by the hand grip and operatively connected to said catch.

5. A fish-shooting mechanism including an elongated tube carrying a reel and a line connected between the reel and an arrowlike member adapted to be discharged from the tube, the tube having a plurality of openings along its length and a hand grip positioned intermediate its ends, a catch and trigger carried within the hand grip, a single spring within the tube normally extending on both ends of the hand grip and an abutment for the spring at one end of the tube, the arrowlike member adapted to be inserted into the tube end opposite the abutment to compress said spring, the arrowlike member having means engaged by said catch to hold the said member in spring-compressing position until released by the trigger.

6. A fish-shooting mechanism for ejecting an arrowlike member including a two-part tandemly arranged tube, each part having holes along its length, a hand grip having a two-part frame for engaging two ends of the two-part tube to hold the parts in alignment, a spring within the tube normally extending on both ends of the hand grip, an anchorage at one end of the tube for one end of the spring, the arrowlike member adapted to be inserted into the tube at its open end to compress said spring and having a notch therein near its tube-entering end, a catch lever carried by the hand grip and adapted to engage said notch in the arrowlike member to hold it in spring-compressing position and a trigger interconnected with the catch lever to release the arrowlike member.

7. A submarine fishing gun for discharging an arrowlike member including an elongated tandemly arranged plural-part tube carrying a reel, with a line fastened between the reel and the arrowlike member, each tube part having a plurality of spaced openings along their length, a firing spring positioned, when not compressed, in the parts of the tube, the spring having one end anchored to one end of the tube and adapted to be compressed by the arrowlike member adapted to be inserted into the ejector end of the tube, a hand grip interconnected with the tube, a catch carried by the hand grip for holding the arrowlike member when it is inserted into the tube to compress the spring to ejection position, a trigger also carried by the hand grip and operatively connected to said catch, the reel being attached to the tube forward of the hand grip, a support for the line at the ejector end of

the tube, and means, including a spring non-rotatably mounted at the firing spring anchorage end of the tube, for initially holding a relatively free length of the line between the arrowlike member and the support.

8. A submarine gun including an elongated tube carrying a reel with a line connection to an arrowlike member adapted to be discharged from the tube, a compressible spring within the tube and having one end anchored to one end of the tube and adapted to be compressed by said arrowlike member insertable into the tube, a hand grip positioned near the balancing point of the gun, a loading catch carried within the hand grip for engaging the spring-compressing end of the arrowlike member, a trigger also carried by the hand grip and operatively connected to the catch and a safety lock carried by the hand grip for locking the trigger.

9. For a submarine gun including an elongated tube carrying a reel with a line interconnected between it and an arrowlike member, a compressible spring within the tube and having one end anchored to one end of the tube and adapted to be compressed by the arrowlike member insertable into the tube, a hand grip positioned near the balancing point of the gun, a loading catch carried within the hand grip for engaging the spring-compressing end of the arrowlike member, a trigger also carried by the hand grip and operatively connected to the catch, a safety lock carried by the hand grip for locking the trigger in either of two positions, one position preventing the said catch from engaging the arrowlike member, the other position being the loaded one.

10. For a submarine gun including an elongated tube carrying a reel with a line interconnected between it and an arrowlike member, a compressible spring within the tube and having one end anchored to one end of the tube and adapted to be compressed by the arrowlike member insertable into the tube, a hand grip positioned near the balancing point of the gun, a loading catch carried within the hand grip for engaging the spring-compressing end of the arrowlike member, a trigger also carried by the hand grip and operatively connected to the catch, a safety lock carried by the hand grip for lock-

ing the trigger, said trigger having an arm with a projection extending at an angle to the arm, the safety lock comprising a movable member having a finger adapted to engage said arm projection on either side thereof, depending on the position of the trigger, means for operating the safety lock.

11. A submarine gun including an elongated tube carrying a reel with a line interconnected between it and an arrowlike member, a compressible spring within the tube and having one end anchored to one end of the tube and adapted to be compressed by the arrowlike member insertable into the tube, the gun having a two part hand grip, each having along its top portion a semi-circular formation to receive a half circumferential part of the tube, means for fastening the two parts of the hand grip together so as to grip the tube, a loading catch pivotally carried within the hand grip, a trigger also carried by the hand grip and operatively connected to the catch, a spring acting on the trigger to normally move it and the catch to loading position, the tube having an opening therein to allow the end of the catch to protrude into the tube into a position to engage the arrow-like member when it is pushed to loading position.

12. A submarine fishing gun for discharging an arrow-like member including an elongated tandemly arranged plural-part tube having a reel attached thereto and a line interconnected between it and the arrowlike member, each having a plurality of spaced openings along their length, a firing spring positioned, when not compressed, in the parts of the tube, the spring having one end anchored to one end of the tube and adapted to be compressed by the arrow-like member adapted to be inserted into the ejector end of the tube, a hand grip interconnected with the tube, a catch carried by the hand grip for holding the arrow-like member when it is inserted into the tube to compress the spring to ejection position, a trigger also carried by the hand grip and operatively connected to said catch, a safety lock carried by the hand grip for locking the trigger in at least one position to prevent the trigger being pulled to discharge the gun.

CHARLES H. WILEN.
